(57) **CLAIM**

The ornamental design for a portable electronic device stand, as shown and described.

DESCRIPTION

FIG. 1 is a perspective view of a portable electronic device stand, showing my new design in an unfolded configuration ready for use;

FIG. 2 is a perspective view thereof, illustrated in a folded configuration;

FIG. 3 is a left-side elevational view of FIG. 2, the right-side elevational view being a mirror image thereof;

FIG. 4 is a rear elevational view of FIG. 2;

FIG. 5 is a front elevational view of FIG. 2;

FIG. 6 is a top plan view of FIG. 2;

FIG. 7 is a bottom plan view of FIG. 2;

FIG. 8 is a perspective view of FIG. 1, illustrated in-use with a portable electronic device; and,

FIG. 9 is a perspective view of FIG. 2, illustrated as stored in the folded configuration in a wallet.

The broken lines showing a portable electronic device in FIG. 8 and a wallet in FIG. 9 depict environmental matter and form no part of the claimed design.
